UNITED STATES PATENT OFFICE.

HEMAN OSBORNE, OF SPRINGFIELD, MASSACHUSETTS.

SHUTTER-WORKER.

953,703.

Specification of Letters Patent. Patented Apr. 5, 1910.

Application filed November 28, 1908. Serial No. 464,911.

To all whom it may concern:

Be it known that I, HEMAN OSBORNE, a citizen of the United States of America, and resident of Springfield, in the county of 5 Hampden and State of Massachusetts, have invented certain new and useful Improvements in Shutter-Workers, of which the following is a full, clear, and exact description.

This invention relates to a somewhat well known class of devices for operating hinged window blinds or shutters from the inside of a room without the necessity of opening a window, which comprise a worm-wheel carrying an externally located shutter-operating lever-arm, a worm in mesh with the worm wheel and internally accessible means for imparting back and forth rotative movements to the worm for closing or opening movements of the shutter.

It is regarded as highly desirable to employ non-metallic cords having winding and unwinding engagements with the part of the device in which the worm is comprised, for imparting the reversed rotative movements 20 to the worm, in preference to metallic chains and the adaptation of the device for the operative connections of the latter; and a principal object of this invention is to produce a shutter-operating device, of the general class 25 above indicated, in which not only cords are employed as the worm operating equipments, but such provisions are made for the retention of the cords in their proper relations to the worm comprising element of 30 the device that assurance is had that the device, when fitted partly into a mortise therefor in the window frame or casing, so that the place of engagement of the cords with the worm element is not accessible, ever 35 reliably remains proof against derangement because of any possibility of the cords becoming bound or obstructed in their properly guided winding and unwinding engagements. And in pursuance of this object the 40 aim of the invention is to provide certain simple, cheaply and practicably produced and easily assembled equipments located and coöoperating between parts of the supporting frame of the device and portions appurtenant to the worm with which the cords 45 having alternately their winding and unwinding engagements.

Another object is to so construct and arrange the parts of the shutter operating device that the latter is rendered applicable, either as a "right" or "left" in any situ-

ation desired and without necessitating the construction of specially formed sets of the devices for use at different sides of a window casing. And another object is to render the 60 device adaptable for its operating action on shutters on which the slotted arm engaging plate may be variably located.

To these ends the invention consists in the combination or arrangement of parts and 65 the construction of certain of the parts all substantially as hereinafter described in conjunction with the accompanying drawings, and as particularly set forth in the claims.

In the drawings:—Figure 1 is a vertical 70 sectional view through the shutter worker and through the portion of a window casing at which it is fitted; Fig. 2 is a horizontal sectional view as taken substantially on line 3—3, Fig. 1,—the worm and one of the hub- 75 like extensions thereof being, however, represented in plan view. Fig. 3 is a horizontal sectional view, on a larger scale, through the principal portion of the shutter worker, taken on line 3—3, Fig. 1. Fig. 4 is a perspective view of the separate parts of a fitting employed in duplicate at the inner side of a window casing for the guidance of the cords from their horizontal to their vertical courses. Fig. 5 is a perspective view showing in separated relations the worm wheel 80 and the longitudinally distensible shutter operating lever arm which is rigidly connected to the worm wheel; Fig. 6 is a perspective view of the bracket frame of the shutter 85 worker; Fig. 7 is a rear or inner face view of the shutter, and Fig. 8 is a perspective view of one of the wheels for inclosing the cord encircled portion of the worm comprising element. 90

Similar characters of reference denote corresponding parts in all of the views.

In the drawings:—A represents a bracket frame to be fitted to a window frame or casing by means of screws through the bracket 100 plate a. Said bracket frame comprises an outwardly extending casing B of which B² is the removable or cover section and inwardly extended opposed lugs C C. A worm wheel D is inclosed and rotatively supported 105 in the casing B and the same has affixed thereto a shutter operating lever arm E.

F represents a worm unitary with and centrally related to opposite hub-like extensions b b which are provided with deep helical cord accommodating and guiding grooves, e. The said worm and its hub like grooved

extensions which are to all intents and purposes the same as integrally formed, have an axial bore from end to end therethrough.

5 G G represent cup-shaped shells having in their backs f central axle accommodating apertures g and also having each a perforation h beyond the center; and these cup-shaped shells are set with their backs against the inner faces of said lugs C C and have 10 their annular walls surrounding and inclosing the aforesaid spirally grooved hub-like extensions; and the annular walls have apertures i therethrough, the one of which is near the top of one shell while the other is 15 near the bottom of the other shell, as to be clearly perceived in Fig. 7.

The axle pin m is passed with a driving fit through the lug, through the central apertures in the shell backs and through the 20 bore of the double hub worm; and in order that cup-shaped shells may be always held against any rotative displacement, but always with their apertures i one near the top and the other near the bottom, screws o 25 are employed which have thread engagements through and from the outer side of the lugs C and have their reduced and non-threaded inner extremities engaged in the aforementioned non-axial perforations in 30 the plane backs of the shells. Two cords are employed having winding and unwinding engagements with the grooved hub-extension and passing therefrom horizontally and inwardly through suitable openings therefor 35 in the window frame over and partially around cord guiding devices t which are inwardly located on or fitted into the window frame. The cords have such reversed arrangements and capabilities for action that 40 when one cord is drawn upon and unwound,—rotating the double hub worm, for causing, through the partial rotary movement of the worm wheel, in mesh therewith, a swinging shutter operating movement of 45 the lever arm E,—the other cord will be wound up on the spirally grooved hub with which it is engaged; and, of course, when the wound up cord is drawn upon, to reversely operate the shutter worker, the cord 50 which had previously been drawn, and unwound, is rewound on the spirally grooved hub to which its end is secured.

The shutter operating arm E comprises a bar section s of longitudinally channeled 55 form and having a longitudinal slot u in its back, and a second bar section v , slidably fitted in the channel of the bar section s , having at its outer extremity an angularly extended shouldered lug w for engagement 60 in a well known manner, common in shutter workers, in the slot x in the angular horizontally applied shutter plate. The screws z which have their heads against the back 65 of the first bar section have their shanks passed freely through the slot u , and they

have screw engagements in tapped holes therefor which are in the second bar section v .

By loosening the screws, moving the bar section v inwardly or outwardly and again 70 turning up the screws, the lever arm is shortened or lengthened so that its shutter engaging end lug is nearer or farther from the center of the partial rotary movement of the worm wheel whereby the radius of the arc 75 movement may be varied and the device adapted to meet different requirements for different shutters as called for by the widths of the shutters and the most available location on them of the slotted angle plate y . 80 The shutter worker in complete form with the exception of the cord guiding fittings J J may be made up in stock with the operating cord in their proper winding and unwinding engagements and the builders or 85 purchasers of the shutter workers will have to give no heed to adjustments or fixing of the cords relatively to the grooved hub-extensions of the worm, as assurance of their retention in their proper working relations 90 is had by the provision of the cup-shaped shell made and applied as hereinabove fully and particularly described; and there can be no derangement of their cords in their relations to the double hubbed worm at any 95 time during the use of the shutter worker,—an important consideration when it is taken into account that the most important working portions of the device are located in a mortise in the window frame and not readily 100 accessible after the shutter worker has been secured by screw in its proper position.

I claim:—

1. In a shutter-worker, a bracket-frame to be fitted to a window-frame, having an outwardly extended casing and inwardly extended opposed lugs, a worm-wheel, rotatively fitted in said casing and carrying a shutter-operating lever arm, a worm having opposite hub-like extensions, which are provided with helical guiding grooves, rotatively supported by and between said lugs, cup-shaped shells having their backs against the inner sides of, and detachably secured to, said lugs having their annular walls surrounding the spirally grooved opposite hub like extensions of the worm wheel and having apertures, one of which is near the top of one shell while the other is near the bottom of the other shell, flexible operating 110 means having winding and unwinding engagements with said grooved extensions, and passing therefrom horizontally and inwardly through the window-frame and guiding devices for said flexible operating 115 means inwardly located on the window frame.

2. In a shutter-worker, a bracket frame to be fitted to a window frame, having an outwardly extended casing and inwardly ex- 120

tended opposed lugs, a worm wheel rotatively fitted in said casing and carrying a shutter operating lever arm, a worm having, and centrally between, opposite hub like extensions which are provided with helical cord-guiding grooves and which worm and hubs have an axial bore from end to end therethrough, cup shaped shells having their backs centrally apertured and also having 10 perforations outwardly beyond their centers, and set against the inner faces of said lugs, and having their annular walls surrounding the said spirally grooved hub extensions, and having apertures, one of which 15 is near the top of one shell while the other is near the bottom of the other shell, an axle pin passed through the lugs, the central apertures in said shell-backs, and the bore of the double hubbed worm, screws having 20 thread engagements through and from the outer sides of said lugs and having their ends engaged in the non-axial perforations in the shell-backs, cords having winding and unwinding engagements with said grooved 25 hub extensions, and passing therefrom horizontally and inwardly through the window-frame, and cord guiding devices inwardly located on the window-frame.

3. A shutter-worker, comprising in combination with a casing, a worm-wheel journaled in said casing, a worm-gear mounted outside said casing and meshing with said worm-wheel, hubs having spiral channels located on each side of said worm-gear, flexible 35 operating means wound on said hubs, and casings inclosing said hubs and having apertures opposite the points of said hubs where said operating means are intended to leave, whereby said operating means are 40 directed to render said worker applicable to either left or right shutters.

4. A shutter-worker, comprising in combination, a worm-wheel, a wheel casing surrounding said wheel and carrying externally 45 a worm-gear in mesh with said wheel, oppositely disposed hubs carried by said worm-

gear, and having spiral channels formed therein, and oppositely wound operating cords secured to said hubs.

5. In a shutter worker, a bracket frame to 50 be fitted to a window casing, supporting, in mesh with each other, an axially vertical worm-wheel and an axially horizontal worm, means for imparting rotative movements to the worm, a shutter operating arm 55 extending radially of, and on a plane at right angles to, the axis of the worm wheel, comprising two longitudinally slideable members, slideable upon one another, one of said members being projected from the worm 60 wheel, and the other member having means for a sliding engagement with a fixture on a shutter, and means for detachably confining the one member of the arm in its longitudinal adjustment on the other. 65

6. The combination with a window casing and a shutter hinged to the casing and provided, adjacent a horizontal edge portion thereof, with a metallic fixture comprising a horizontal slotted flange, of a bracket 70 frame to be secured on the window casing, supporting, in mesh with each other, an axially vertical worm wheel and an axially horizontal worm, means for imparting rotative movements to the worm, and a shutter- 75 operating-arm comprising two relatively longitudinally slideable members, one of which is affixed to and radially extended from the worm wheel, and the other member having at its outer extremity an angularly 80 turned lug for a sliding engagement in the slotted horizontal flange on the fixture on the shutter, and means for detachably confining the one member of the arm in its longitudinal adjustment on the other. 85
